UNITED STATES PATENT OFFICE.

CARL PRÖTT, OF HAGEN, GERMANY.

MECHANISM FOR CONVERTING RECIPROCATORY MOTION INTO ROTARY MOTION.

1,115,790.

Specification of Letters Patent. Patented Nov. 24, 1914.

Application filed March 14, 1914. Serial No. 824,787.

To all whom it may concern:

Be it known that I, CARL PRÖTT, subject of the King of Prussia, residing at 14 Humboldtstrasse, Hagen, in Westphalia, Germany, have invented certain new and useful Improvements in Mechanism for Converting Reciprocatory Motion into Rotary Motion, of which the following is a specification.

This invention relates to mechanism for converting reciprocatory motion into rotary motion and more particularly to that class of mechanism in which an eccentric member mounted at an inclination to a rotary shaft is interposed between reciprocating members and the rotary shaft and in which an auxiliary disk or like member is interposed between the eccentric member and the reciprocating parts, being so mounted as not to turn with the rotary shaft, the stroke of the reciprocating members being capable of variation by adjusting the inclination of the eccentric member.

The object of the present invention is to provide improved means for enabling the inclination of the eccentric member to be varied and for this purpose it is provided at right angles to its pivotal axis and at each side of the rotary shaft on the opposite side to the reciprocating members with a toothed segment in which a toothed sector or wheel engages, the latter being actuated by toothed racks which are mounted on a collar splined on the rotary shaft.

In order that the present invention may be more clearly understood reference is made to the accompanying drawings showing the preferred construction of my improved mechanism.

Figure 1 is a vertical section through such parts of the mechanism as are necessary to illustrate the present invention. Fig. 2 is a plan view with the eccentric member removed. Fig. 3 is a vertical section showing a slight modification of the invention.

In Figs. 1 and 2 are shown two members *a* and *b*, the member *a* rotating with the shaft *c* and being supported in bearings *e* in the casing *d* and having a concave upper face to receive the adjustable member *b* which latter constitutes the eccentric member hereinbefore referred to. Supported by means of a ball bearing *m* on the eccentric member *b* is an auxiliary disk or member *n* which is also supported from the hub of the eccentric member *b* by means of a ball bearing *o*. The disk *n* carries two trunnions *p*

mounted in sliding bearings *q* adapted to move up and down within the curved guides *r* on the casing *d*. The heads *s* of piston rods *t* working within cylinders are mounted in the disk *n*.

According to the present invention the eccentric member *b* is provided with toothed segments *f* on both sides of the shaft *c*, these segments working in grooves *u* in the member *a* and meshing with toothed sectors *g* which pass through slots in the member *a* and are either mounted on a transverse pin *c'* on the shaft *c* as illustrated in Fig. 1 or housed in the member *a*, the sectors being preferably arranged at one side of the shaft so that the pitch circle of the sectors touches a plane passing through the center of the shaft at right angles to the sectors. Mounted on a collar *h* which is splined on the shaft *c* are toothed racks *h* meshing with the toothed sectors *g*. If desired the toothed racks may be suitably supported laterally by means of stops *h'* (Fig. 2).

In Fig. 1 the collar *h* is shown in its highest position the eccentric member *b* being displaced to the greatest possible extent toward the right so that the greatest possible reciprocation of the piston rods *t* takes place. If the collar *h'* is moved downwardly the toothed racks *h* will rotate the sectors *g* until the axis of the eccentric member *b* coincides with the axis of the shaft *c* whereupon the reciprocation of the piston rod *t* will be reduced to zero. The collar *h* may be moved in any desired manner as, for example, by means of a fork *r'* mounted upon a shaft *i'* which passes laterally through the casing *d*. Since the casing *d* is kept constantly filled with lubricant it is necessary to provide a stuffing box for the shaft *i'* but as this shaft is only occasionally rotated and only to a small extent, a very simple packing may be employed.

In Fig. 3 a mechanism is illustrated in which the eccentric member *b'* is not supported on bearings in the casing *d* but is mounted on trunnions *p* on the shaft *c* and supported in ball bearings *v* in the disk *n'* whose trunnions *p'* are supported in sliding bearings *q* as described with reference to Fig. 1.

In the modification illustrated in Fig. 3 the toothed racks *h* are shown adapted to rotate spur wheels *g'* which do not directly mesh with the segments *f* on the member *b'* but are compounded with smaller pinion

wheels *g* which are in gear with the segments *f*. By means of this reducing gear the power required to move the member *b'* is reduced, but the requisite movement of the toothed racks is correspondingly increased.

I claim:

1. Mechanism for converting reciprocatory into rotary motion comprising in combination a rotary shaft, an adjustably inclined member revolving with said shaft, reciprocatory members, a member interposed between said reciprocatory members, an adjustably inclined member stationary relatively to said shaft, toothed segments on said adjustably inclined member, toothed racks splined on said shaft for imparting motion to said segments, and lever mechanism for sliding said racks on said shaft.
2. Mechanism for converting reciprocatory into rotary motion comprising in combination a rotary shaft, an adjustably inclined member revolving with said shaft, an element supported on said adjustably inclined member so as not to rotate therewith, reciprocatory members connected to said element, a casing inclosing said members and element, toothed segments on said adjustably inclined member, toothed racks splined on said shaft for imparting motion to said segments, a lever operating said toothed racks, and an operating shaft supporting said lever and passing through said casing.
3. Mechanism for converting reciprocatory motion into rotary motion comprising in combination, a rotary shaft, reciprocatory members, a concave and adjustably inclined

disk rotatable with said shaft, a convex member resting on said disk and connected to said reciprocatory members, toothed segments on the convex member, toothed racks for imparting motion to said segments, and lever mechanism for sliding said racks.

4. Mechanism for converting reciprocatory motion into rotary motion comprising in combination a rotary shaft, reciprocatory members, a concave disk rotatable in unison with said shaft, a convex member resting on said concave disk, an element connected to said reciprocatory members and mounted stationarily upon said convex member, toothed segments on the convex face of said convex member, toothed racks splined on said shaft for imparting motion to said segments, and lever mechanism for sliding said racks on said shaft.

5. Mechanism for converting reciprocatory motion into rotary motion comprising in combination a rotary shaft, reciprocatory members, a concave disk rotatable in unison with said shaft, a convex member resting on said concave disk, an element connected to said reciprocatory members and mounted stationarily upon said convex member, toothed segments on the convex face of said convex member, toothed sectors meshing with said segments and housed in slots in said concave disk, and slideable toothed racks in gear with said sectors.

In testimony whereof I affix my signature in presence of two witnesses.

CARL PRÖTT. [L.S.]
